United States Patent Office

Des. 179,007
Patented Oct. 23, 1956

179,007

FINGER RING

Paul A. Kaiser, Indianapolis, Ind., assignor to Herff Jones
Co., Indianapolis, Ind., a corporation of Indiana

Application November 1, 1955, Serial No. 38,680

Term of patent 7 years

(Cl. D45—10)

FIG. 1

Fig. 1 is a top plan view of a finger ring showing my new design;

Fig. 2 is a side elevational view thereof; and

Fig. 3 is an opposite side elevational view thereof.

I claim:

The ornamental design for a finger ring, as shown.
